FEEDING DEVICE FOR MILLS

Alexus C. Lindgren, Chicago, and Clemma R. Raney, Riverside, Ill., assignors to International Harvester Company, a corporation of New Jersey

Application April 20, 1934, Serial No. 721,422

3 Claims. (Cl. 83—11)

The invention relates to grinding mills of the hammer type for grinding feed and roughage, such as corn cobs.

Such mills usually comprise a cylindrical, upright drum housing a grinding rotor, the material to be ground being fed from a hopper by gravity through a throat portion and thence into the drum through a feed opening formed in a side of the drum. The end of the throat portion is usually flush with the wall of the drum, so that a substantial space exists between the discharge end of the throat and the adjacent face of the rotor. Further, the face of the rotor is provided with shredders or breaker elements that pass across the feed opening to receive and preliminarily reduce roughage, such as cobs, before they pass to the periphery of the drum for final grinding by the hammers. It is found in practice that the shredder teeth do not properly engage the infed cobs, due to the space between the end of the throat and the face of the rotor where it carries the shredders.

Accordingly, the invention more particularly relates to the provision of an adjustable feed attachment for the throat that will carry cobs and other roughage in closer to the rotor and its shredders, so that the latter will better perform their function.

The object of the invention, therefore, is to provide an improved feeding mechanism for mills.

Another object is to make such device adjustable.

Still another object is to provide such device which will be simple and effective for the purposes intended, and to mount the same on the mill without materially altering the structure of the mill.

Further, it is an object to provide a pivotally mounted extension feeder for the purpose mentioned, which is swingable in and out between the throat of the hopper and the rotor in the reducing drum.

Other objects will be apparent to those versed in this art as the disclosure is more fully made.

In the drawing showing an illustrative and practicable example which the invention may assume in practice,—

Figure 1 is a vertical, substantially central, cross sectional view through a hammer type mill, showing the improved extension feed device associated therewith; and,

Figure 2 is a detail elevational face view of the extension feeder, as viewed from the line 2—2 appearing in Figure 1.

The mill is carried on a base 10 and comprises the usual circular drum 11 having spaced par-

allel sides to form a reducing chamber 12. One side of the drum carries a shaft 13 journaled in the bracket 14, said shaft being turned by pulleys 15.

The shaft 13 projects into the chamber 12 to carry and turn a rotor 16 having peripheral hammers 17 for grinding the material in process. The side of the drum 11 shown at the left in Figure 1 is formed with an elongated, upright feed opening 18, also shown in Figure 2. Braces 19 serve to support a feed hopper 20 from this side of the chamber, said hopper including a narrowed down throat portion 21 that comes about flush with the feed opening 18, but being somewhat smaller in size, as shown. The adjacent face of the rotor 16 carries radially inwardly of the hammers 17, a series of shredder teeth 22, so located that they pass across the feed opening 18 to engage and preliminarily break up cobs and the like.

In the form herein shown, the feed opening 18 is rectangular and vertically disposed, the lower edge thereof being rounded to conform to the trough shape of the feed throat 21. The wall 11 above the feed opening 18 carries a pair of spaced hinges 23 for hingedly or pivotally hanging an extension feeder device 24. This device in the present instance assumes the form of an upright rectangular loop having a rounded lower edge to conform in shape to the feed opening 18, said loop being fitted between the periphery of the feed opening 18 and the discharge end of the throat 21, the loop further having a width sufficient to span the space between the end of the throat and the adjacent wall 11. In fact, the width of the extension feeder is purposely determined to enable the lower discharge edge thereof to be brought into close proximity to the vertical plane in which the shredder teeth 22 move.

The under edge of the loop 24 carries an ear 25 to which is pivotally connected an adjusting screw rod 26, which has its other end slidably passed through a bracket 27, there being an adjusting nut 28 on the rod in back of the bracket to enable adjustment of the rod and consequently the position of the loop relative to the rotor and its teeth 22.

In use it can be seen that the extension feed device 24 can be adjustably set in and out with respect to the rotor and its shredder teeth 22, so as to feed cobs and the like at the exact point to cause the teeth 22 aggressively to engage and break the material preliminarily in the most efficient manner.

It is the intention to cover all changes and mod-

ifications not departing from the spirit and scope of the invention which is hereinafter claimed.

What is claimed is:

1. A hammer mill comprising an upright drum providing a reducing chamber having a peripheral reducing screen, a rotor operable in the chamber having peripheral hammers cooperable with the screen in reducing material, one side of the drum having a feed opening, a hopper carried by the drum and having a throat portion terminating substantially at the edge of the feed opening and slightly inwardly spaced therefrom, whereby the throat portion serves to feed material from the hopper to the adjacent face of the rotor, breaker devices on the said face of the rotor located to receive the material and preliminarily break it up before it passes to the hammers and screen, and an extension feeder device located between the discharge end of the throat and the edge of the feed opening, said feeder device comprising a looped member substantially surrounding the said end of the throat and serving to feed the material into close proximity to the path of movement of the breaker devices.
2. A hammer mill comprising an upright drum providing a reducing chamber having a peripheral reducing screen, a rotor operable in the chamber having peripheral hammers cooperable with the screen in reducing material, one side of the drum having a feed opening, a hopper carried by the drum and having a throat portion terminating substantially at the edge of the feed opening and slightly inwardly spaced therefrom, whereby the throat portion serves to feed material from the hopper to the adjacent face of the rotor, breaker devices on the said face of the rotor located to receive the material and preliminarily break it up before it passes to the hammers and screen, an extension feeder device located between the discharge end of the throat and the edge of the feed opening, said feeder device comprising a looped member substantially surrounding the said end of the throat and serving to feed the material into close proximity to the path of movement of the breaker devices.

charge end of the throat and the edge of the feed opening, said feeder device comprising a looped member substantially surrounding the said end of the throat and serving to feed the material into close proximity to the path of movement of the breaker devices, and means for adjustably positioning said extension feeder device substantially axially of the throat portion of the hopper and relative to the said breaker devices.

3. A hammer mill comprising an upright drum providing a reducing chamber having a peripheral reducing screen, a rotor operable in the chamber having peripheral hammers cooperable with the screen in reducing material, one side of the drum having a feed opening, a hopper carried by the drum and having a throat portion terminating substantially at the edge of the feed opening and slightly inwardly spaced therefrom, whereby the throat portion serves to feed material from the hopper to the adjacent face of the rotor, breaker devices on the said face of the rotor located to receive the material and preliminarily break it up before it passes to the hammers and screen, a swingably supported extension feeder device located between the discharge end of the throat and the edge of the feed opening, said feeder device comprising a looped member substantially surrounding the said end of the throat and shaped to conform to the shape of the throat and serving to feed the material into close proximity to the path of movement of the breaker devices, and manually adjustable means located exteriorly of the throat portion of the hopper for swinging the feeder device substantially coaxially of the throat portion and adjustably positioning it relative to said breaker devices.
